UNITED STATES PATENT OFFICE

109,929

DESIGN FOR A GAME BOARD OR SIMILAR ARTICLE

Isidor S. Rosen, Brooklyn, N. Y.

Application April 4, 1938, Serial No. 76,273

Term of patent 3½ years

To all whom it may concern:

Be it known that I, Isidor S. Rosen, a citizen of the United States, residing at Brooklyn, in the county of Kings and State of New York, have invented a new, original, and ornamental Design for a Game Board or Similar Article, of which the following is a specification, reference being had to the accompanying drawing, forming part thereof.

In the drawing

The sole figure is a top plan view of a game board showing my new design; the game board herein shown being of conventional thickness.

I claim:—

The ornamental design for a game board or similar article as shown, and described.

ISIDOR S. ROSEN.
